UNITED STATES PATENT OFFICE

SAMUEL F. LEDERER, OF CHICAGO, ILLINOIS, ASSIGNOR TO JAC. LEDERER, INC., OF CHICAGO, ILLINOIS, A CORPORATION OF ILLINOIS

LUNCH ROOM STOOL

Application filed June 17, 1929. Serial No. 371,377.

The main objects of this invention are to provide an improved swivel seat lunch room stool of the type which has back rests; to provide means for yieldably retaining the seat of the stool in a suitable position relative to a lunch counter so that customers may conveniently seat themselves without adjusting the stool; and to provide means for rotating seats of this kind to a predetermined position after occupants arise from them so as to bring the back rests of the unoccupied seats of a lunch counter into alinement for presenting an orderly appearance.

An illustrative embodiment of this invention is shown in the accompanying drawings, wherein—

Fig. 1 is a front elevation of a lunch room stool, partly in section.

Fig. 2 is a side elevation of the stool.

Fig. 3 is an enlarged fragmentary section taken on the line 3—3 of Fig. 1.

Fig. 4 is a horizontal section, taken on the line 4—4 of Fig. 3.

Fig. 5 is a section taken on the line 5—5 of Fig. 3.

Fig. 6 is a bottom plan of the base of the stool.

In the form shown, the improved stool comprises a standard, on which is rotatably mounted a seat having a back rest. Secured to the seat and standard, is a spring which yieldably holds the seat on the standard and also urges the seat into a predetermined position relative to the standard when the stool is unoccupied.

In the construction illustrated, the standard includes a hollow post 1, on the lower end of which is mounted a base 2, provided with a top wall 3, which is located within the lower end of the post. Seated in the upper end of the post 1, is a cylindrical cup 4 having a peripheral flange 5 which is welded or secured in any other suitable manner to a flange 6 on the upper end of the post 1. The bottom of the cup 4 is provided with a central aperture 7 and a pair of diametrically opposite apertures 8. Mounted in the cup 4, is a support 9 of cylindrical shape which has an inclined cam surface 10 on its upper end. On the lower end of the support 9, is a pin 11

which is adapted to extend into either of the apertures 8 for retaining the cam surface 10 of the support 9 in one of two oppositely inclined positions.

Rotatably mounted on the post 1, is a seat 12 which includes a back rest 13. Secured to the bottom of the seat 12 is a spider 14, on which is threaded a depending support 15 having an inclined cam surface 16 which engages the cam surface 10 of the support 9. The support 15 of the seat extends into the cup 4 and rests upon the support 9. Extending through central apertures in the supports 9 and 15, and through the central aperture 7 in the bottom of the cup 4, is a bolt 17 which is secured at its upper end to the spider 14. The lower end of the bolt 17 is provided with an eyelet 18, to which is attached a spring 19. The spring 19 extends axially through the hollow post 1 and through an aperture in the top wall 3 of the base 2. Secured to the lower extremity of the spring, is a pin 20, which bears against the lower face of the top 3.

In operation, when the seat is unoccupied, it is normally held in the position shown in Fig. 3, so as to retain the back rest 13 substantially normal to a lunch counter. When a plurality of lunch room stools of this kind are mounted in front of a lunch counter, the back rests of all the seats are retained in a uniform position relative to the counter so as to present an orderly appearance. A customer may conveniently approach the seat 12 from one side of the stool and rotate the seat in the direction of the lunch counter after he has seated himself.

When the seat is vacated, the spring 19 restores the seat to its normal unoccupied position. The support 9 may be adjusted so as to position the back rest 13 on the left hand side of the post 1 rather than on the right hand side thereof, as shown in Fig. 3, by inserting the pin 11 into the right hand aperture 8 of the cup 4.

Although but one specific embodiment of this invention has been herein shown and described, it will be understood that details of the construction shown may be altered or omitted without departing from the spirit of

this invention as defined by the following claims:

I claim:

1. A device of the class described comprising a hollow upright post, a seat having a back rest rotatably mounted on said post, supports on said seat and post respectively having opposed inclined cam surfaces, an upright bolt connected to said seat and extending downwardly through said cam surfaces, and a spring connected at one extremity to the lower end of said bolt and at the other extremity to the lower end of said post for urging said cam surfaces together to yieldably retain said seat and back rest in a predetermined position relative to said post.
2. A device of the class described comprising a hollow upright post, a seat having a back rest rotatably mounted on said post, a cup mounted on the upper end of said post having an aperture in the bottom thereof, a support in said cup having an inclined cam surface, a pin on said support extending through said aperture for securing said support against movement relative to said post, a support on said seat having an inclined cam surface engaging said first mentioned cam surface, and a spring extending axially through said post connected at one extremity to said seat and at the other extremity to the lower end of said post for yieldably retaining said seat and back rest in a predetermined position relative to said post.
3. A device of the class described comprising a hollow upright post, a seat having a back rest rotatably mounted on said post, a cup mounted on the upper end of said post having spaced apertures in the bottom thereof, an adjustable support in said cup having an inclined cam surface, a support on said seat having an inclined cam surface coacting with the inclined surface of said adjustable support for retaining said seat in a predetermined position, and a pin on said adjustable support adapted to extend into one of said apertures for selectively retaining said seat in a predetermined position relative to said post.
4. A device of the class described comprising a hollow upright post, a seat having a back rest rotatably mounted on said post, a cup mounted on the upper end of said post having spaced apertures in the bottom thereof, an adjustable support in said cup having an inclined cam surface, a support on said seat having an inclined cam surface coacting with the inclined surface of said adjustable support for retaining said seat in a predetermined position, a pin on said adjustable support adapted to extend into one of said apertures for selectively retaining said seat in a predetermined position relative to said post, and a spring attached at one extremity to said seat and at the other extremity to said

post for urging said cam surfaces together to restore said seat to said predetermined position.

Signed at Chicago this 11th day of June, 1929.

SAMUEL F. LEDERER.
